Primary Examiner — Gino Colan(74) *Attorney, Agent, or Firm* — Dorsey & Whitney LLP**CLAIM**

The ornamental design for a top cap for a ladder, as shown and described.

DESCRIPTION

FIG. 1 is a front perspective view of a top cap for a ladder showing our new design;

FIG. 2 is a rear perspective view of the top cap for a ladder shown in FIG. 1;

FIG. 3 is a front view of the top cap for a ladder shown in FIG. 1;

FIG. 4 is a rear view of the top cap for a ladder shown in FIG. 1;

FIG. 5 is a right side view of the top cap for a ladder shown in FIG. 1;

FIG. 6 is a left side view of the top cap for a ladder shown in FIG. 1;

FIG. 7 is a top view of the top cap shown in FIG. 1; and, FIG. 8 is a bottom view of the top cap for a ladder shown in FIG. 1.

Any broken lines shown in the figures are for the purpose of illustrating boundaries and form no part of the claimed design.

1 Claim, 7 Drawing Sheets(56)
